UNITED STATES PATENT OFFICE

2,304,360

ELECTRIC LIFTING DEVICE

Frederick W. Horstkotte, Portland, Oreg.

Application December 24, 1940, Serial No. 371,557

6 Claims. (Cl. 143—95)

This invention relates to an electric lift, especially useful in situations requiring a momentary lift impulse of great intensity, as for example in handling logs onto a saw-mill carriage, for turning them and for other work of like character.

It is an object of the present invention to make electric power as instantly available as a steam cylinder with piston heretofore exclusively used for such requirements. The objections to the steam cylinder are many and need not be recited, but they have been accepted as inevitable concomitants of apparatus capable of performing the required function.

Such apparatus is ordinarily used intermittently and for only a very small fraction of total working time, hence it is an object to associate a suitable electric motor with suitable other elements in such a combination that when a starting impulse is manually given, the motor has initial room in its operating cycle to attain speed and power without having to accept substantial load until it has done this; yet it must and does enter the work part of the cycle without shock such as may be expected with employment of a clutch, which in this invention is not used. It is therefore another object of the present invention to provide electrically operated apparatus having operating characteristics as indicated, but omitting a clutch heretofore always deemed necessary.

Succinctly, it is an object of this invention to arrange an electrical substitute for the steam cylinder and piston device, that fulfills all of the functions of the latter at its best and does not have its inherent infirmities, such as a tendency to overshoot due to resilient steam when the load changes, or reversely to drop a load due to steam condensation, often occurring with extreme rapidity. The very substantial waste of power of a steam lifter using steam non-expansively is also avoided.

To comply with Sec. 4888 R. S., I have shown my new invention operatively connected to a loading arm for throwing a log onto a saw carriage. This, however, is only one of the very numerous applications wherein it is an advance over the reciprocating steam cylinder and piston; hence the drawings will not be regarded as limiting but illustrative only. For the scope of the invention, the art is referred to the claims at the close of this specification.

To illustrate mechanism adapted to apply the mechanical principles of this invention, drawings

accompany and are made a part hereof, as follows—

Fig. I is a side elevation of an operative log lifting device for throwing a log onto a saw-carriage that embodies the principle of the present invention and this figure also includes a diagrammatic layout of the electrical connections more completely shown in detail in Fig. VIII;

Fig. II is a left hand end view of the structure shown in Fig. I;

Fig. III is a section taken at III—III, Fig. I;

Fig. IV is a section taken at IV—IV, Fig. I, the last two figures being especially useful to show the position of limit switches and their employment as hereinafter described;

Fig. V is a diagram showing how a pair of limit switches may be used with a single operative cam, the structure being otherwise the same in principle as that shown in Fig. I;

Fig. VI is a view in orthographic projection of Fig. V;

Fig. VII is a view of an alternate construction, useful in cases where a very long stroke is required or where more than two or three limit switches are desirable in each cycle of operation; and

Fig. VIII is a wiring diagram for the structure shown in Fig. I, from which any skilled electrician may make up a wire diagram for any variation thereof employing the same principle.

In the drawings, first considering Fig. I: 1 is an electric motor of the 3 phase squirrel cage type with an exceedingly high starting torque, also capable of carrying a momentary overload of several hundred per cent. 2 is the motor drive shaft and 3 is a shunt brake, see Fig. VIII, and is the single phase circuit for the brake. This type of brake is set by a spring and opened by electromagnets when the motor is taking current.

5 5 is what is commercially called a motorgear, consisting of a casing within which reducing gears run in oil, delivering the motor power to an output shaft 6, at relatively slow speed and correspondingly increased torque. This motorgear will have to be strong enough to operate satisfactorily when the motor is delivering its maximum overload capacity.

A crank 7 is mounted on the shaft 6. It has a crankpin 8 to which one end of the connecting rod 9 is journaled. The other end of the connecting rod 9 is journaled between the forks 10 of the rocker arm 11, which is made rigid with the rock shaft 12. A wrist pin 11 holds the connecting rod 9 operatively between the forks.

The rock shaft 12 is adapted to oscillate under

influence of the motor 1 by means of the transmissions heretofore described and, when so oscillated, will apply great power to the lifter arm 13, a well known device for throwing a log from a log-deck to a saw carriage, as indicated in Fig. II, though always heretofore such a lifter has been operated by a double acting steam cylinder of considerable size. In practice there will be at least two of these lifter arms.

It will be at once apparent that any other severe but short time lift, other than the one shown, may be accomplished by appropriate driven electrically operated devices according to this invention. Note here that a crank or similar transmission has a neutral zone of operation while it is going over its bottom center. Being halted at the bottom center of its stroke or just before it reaches the bottom, and assuming that the reduction in the motorgear is considerable, a motor with a high pullout torque will attain a high speed and consequent pulling power before it must accept any substantial part of the load, represented here by a log L, in dotted outline, then the great momentary overload capacity of the motor will be put to good use, because the lift will be completed well short of the time when the copper windings of the motor can overheat due to abnormal current flow.

It is believed that this marks the first time this inherent motor characteristic has been put to beneficial use, save to occasionally prevent damage when some operated part is stuck.

That this structure may be operated with a facility superior to the steam cylinder lifter which it replaces, may now be examined into.

We will assume that the electric lifter is at rest, as shown at Fig. I, with the crank-pin 8 somewhere within the neutral zone of its revolution, as shown. The limit switch 20 has been opened by the cam 21 on the hub of the crank 7; hence the primary line 22 of the electric motor circuit is dead. The head-sawyer will step on the manually operable, normally open switch 23, thus closing the secondary electric line 24 and 25, whereupon the limit switch 20 is by-passed, the manual switch 23 takes over control, the shunt brake 3 instantly releases and the motor operates the electric lift after the manner described.

If actuation of the manual switch is momentary only, being released as soon as the lift starts, then the limit switch 20 takes over the control, until the cam 21' lifts the arm 30, of the limit switch 31, whereupon the secondary line is again opened with the lifting arm 13 on top in the position shown in Fig. II and the motor stops abruptly.

The brake will stop the motor 1 without overrun sufficient to interfere with successful operation, when a log turner or a device for shoving the log further onto the carriage may be worked, the lifter 13 meanwhile holding the log L exactly where it was placed for any desired length of time, something for which the steam cylinder is not well suited.

If, on the other hand, mere throwing of the log onto the carriage is sufficient, then the operator will keep the manual switch closed until the arm 13 begins the downward part of its cyclic operation, when he releases it and the limit switch 20 assumes control automatically. This cycle of operations is more certain than that of a steam cylinder and does not involve the very large waste of power occasioned by a direct steam pressure in a cylinder.

In Figs. V and VI, there is shown a disc 40, upon which is mounted a single cam 41, co-operative with limit switches 42 and 43. The mode of operation of this form is identical with that shown in Fig. I, but by placement of the limit switches differently, a single cam serves just as well as two cams in the other structure. It will be apparent that cam operated limit switches can be placed adjacent any part having a cyclic path of operation.

Fig. VII illustrates a chain 50 mounted on a driving sprocket 51 and a driven sprocket 52, to which is pinned a connecting rod 53. A single limit switch 54 will be opened by a cam 55, shown as an attachment link of the chain 50. Obviously this structure lends itself well to carrying several more cams than are conveniently disposable within the working cycle of the transmissions of Fig. I. The purpose of this figure is to show that by proper modification of the structure shown in Fig. I an operating cycle of a lifter can be varied even more widely than with the well known steam cylinder lift and with the added advantage that wherever it is stopped, it will stay, indefinitely until it is purposely moved forward. In practice, there are at least two and generally three positions on the lifting side of the operating cycle, with nothing on the return side save a limit switch positioned to stop the crank-pin or equivalent structure within the neutral zone and preferably just at its beginning, lucidly expressed by using a marksman's simile, "at five-o'clock."

Having disclosed my invention and explained its principle so that it can take its proper place in the art, what I claim as new and desire to secure by Letters Patent is:

1. An electric log lifting and moving device comprising a lifter arm, a crank connected to said arm, an electric motor operatively connected to said crank, control means for said motor comprising a power circuit, two automatic limit switches in said circuit, means for operating said limit switches seriatim to stop the motor with the crank in its next succeeding neutral zone, and a normally open manual switch effective to bypass both automatic limit switches for continuous operation of the motor when it is forcibly held in closed position.

2. An electrically operated lifter device comprising a reciprocating lifter crank, means for reciprocating the lifter comprising an electric motor, speed reducing transmission means connected intermediate the motor and the crank, a pair of cams revoluble at crank speed and synchronized therewith, an electric circuit for said motor, a pair of automatic limit switches in said circuit, an operating cam for each switch, a bypass circuit, and a normally open manual switch in said circuit effective upon operation to take over control from both of the automatic limit switches, each limit switch and cam for operating the same being timed to stop the crank in its next succeeding neutral zone.

3. An electric lift comprising an electric motor, a power circuit for said motor, control means comprising a normally open manual switch and two automatic limit switches, a reciprocable lifter, transmissions between the lifter and the motor, a crank forming part of said transmissions, and limit switch operating means synchronous with the crank and timed to operate one of the limit switches and stop the motor with the crank in its nearest neutral zone, the said manual switch ef-

fective to assume and hold control of the motor when manually closed.

4. In an electric lifter, an electric motor therefore, transmissions for said motor effective to change rotary to reciprocating motion at reduced speed, crank and connecting rod means in series with other parts in said transmissions, a pair of revoluble cams synchronized with the crank, a pair of normally closed limit switches arranged to be opened seriatim by the cams to stop the motor and leave the crank in a neutral zone, and a normally open manually operable switch arranged to supersede the control of any given limit switch that may have stopped the motor, to restart the same, each limit switch being effective, seriatim, to stop the crank as it enters its next neutral zone.

5. An electric lifting device comprising an electric motor, a crank driven thereby, speed reducing transmissions therebetween, a lifter operable by the crank, said transmissions comprising one part having a cyclic path of movement, cams made

rigid with said last named part, a pair of normally closed limit switches arranged to be opened seriatim by said cams, each of said limit switches effective to stop the motor leaving the crank in its nearest neutral zone when contacted by a cam, and a normally open manual switch effective to by-pass both limit switches when closed.

6. An electric lifting device comprising an electric motor, a crank, speed reducing transmissions therebetween, a lifter device operable by said crank, a rotary part of said transmissions synchronized with the crank, a plurality of normally closed limit switches disposed adjacent said rotary part, means carried by said rotary part to open said limit switches seriatim, each limit switch effective to stop the motor when opened, concurrently stopping the crank in its next neutral zone, and a normally open manually operable switch effective when operated to take over the entire control of the motor.
